UNITED STATES PATENT OFFICE

144,149

DESIGN FOR A GAME BOARD

Carl G. Anderson and Leamon G. Livesay,
Pryor, Okla.

Application July 3, 1945, Serial No. 120,480

Term of patent 14 years

(Cl. D34—5)

To all whom it may concern:

Be it known that we, Carl G. Anderson and Leamon G. Livesay, citizens of the United States, residing at Pryor, in the county of Mayes and State of Oklahoma, have invented a new, original, and ornamental Design for a Game Board, of which the following is a specification, reference being had to the accompanying drawing, forming part thereof.

We claim:

The ornamental design for a game board, as shown.

CARL G. ANDERSON.
LEAMON G. LIVESAY.
